UNITED STATES PATENT OFFICE.

FRANK L. CROSS, OF WOLLASTON, MASSACHUSETTS, ASSIGNOR TO CROSS PAPER FEEDER COMPANY, A CORPORATION OF MAINE.

PAPER-FEEDING MACHINE.

982,255.

Specification of Letters Patent. Patented Jan. 24, 1911.

Application filed April 30, 1908. Serial No. 430,111.

To all whom it may concern:

Be it known that I, FRANK L. CROSS, a citizen of the United States, residing at Wollaston, in the county of Norfolk and 5 State of Massachusetts, have invented certain new and useful Improvements in Paper-Feeding Machines; and I do hereby declare the following to be a full, clear, and exact description of the invention, such 10 as will enable others skilled in the art to which it appertains to make and use the same.

The invention relates to that class of paper feeding machines in which a bank of 15 feathered or fanned out sheets is presented to devices which separate individual sheets from the front of the bank so that they may be removed and presented to machines or devices for further manipulating or acting 20 on them.

In order that the separating devices may operate properly upon the front of the bank of sheets in this class of machines, and may properly separate the individual sheets, the 25 bank of sheets should be so fed to the separating devices that the front edge of the bank will be maintained at a substantially uniform point. So long as the front edge of the bank of sheets is at this point or in 30 advance of it, there should be no feed of the bank, but as soon as the removal of successive sheets from the front of the bank carries the front edge of the bank back of this point, there should be a feed of the 35 bank, and the feed should continue until the front edge of the bank is brought up to the proper point.

It is the object of the present invention to provide a mechanism for feeding the bank 40 of feathered sheets which will automatically act to maintain the front edge of the bank at a substantially uniform point during the separation and removal of the individual sheets from the front of the bank.

One feature of the invention contemplates 45 the provision of a mechanism for feeding forward a bank of feathered or fanned out sheets which will act to feed forward the bank whenever the front edge of the bank 50 is back of a predetermined point, but will remain inactive so long as the front edge of the bank is at or in advance of said point. The bank feeding mechanism is preferably controlled to act in this manner by controlling 55 means coöperating with the front edge

of the bank to render the bank feeding mechanism active when the front edge of the bank is back of a predetermined point.

In addition to the broader features, the invention includes certain further features 60 which may be embodied with especial advantage in machines in which the separation of individual sheets from the front of the bank is effected by combing devices which act to further fan or feather out the top sheets, and which are thrown out of operation when the front edge of the top sheet has been advanced into a definite position. 65

In machines embodying this form of sheet separating devices, the distance between the front edge of the bank and the devices which control the throwing out of the combing devices when the front edge of the sheet has been advanced into proper position, should be adjusted or varied in accordance 70 with the character of the sheets being operated upon. In operating upon comparatively thin sheets, for instance, the front edge of the bank of sheets should be maintained at a comparatively long distance 75 back of the line to which the front edge of the sheet is advanced by the action of the combing devices. In operating upon heavy sheets, however, the front edge of the bank should be maintained at a shorter distance 80 back of this line, in order that the top sheet 85 may be properly separated and advanced to this line during the combing interval. In embodying the invention in machines in which the sheets are separated by combing devices, therefore, means should be provided 90 for relatively adjusting the controlling means for the combing devices, and for the feed of the bank of sheets, to vary the distance between the front edge of the bank 95 and the line to which the front edge of the sheet is advanced by the combing devices, in accordance with the character of the sheets to be operated upon. This adjustment may 100 be secured in any suitable manner, and is preferably secured by adjusting the mechanism for feeding the bank of sheets to vary the point at which the front edge of the bank is maintained, in accordance with the character of the sheets being operated upon.

The various features of the invention will be understood from an inspection of the accompanying drawing, in which the preferred form of the invention is shown embodied in a sheet feeding machine in which the indi- 110

vidual sheets are separated from the front of the bank of sheets by combing rolls operated and controlled by mechanism similar to the mechanism shown and described in Patent No. 812,260, dated February 13, 1906.

5 In the drawing Figure 1 is a side elevation partly in section showing a sheet feeding machine embodying the invention in its preferred form, and Fig. 2 is a detail plan view 10 showing a part of the bank feeding mechanism.

As shown in the drawing, the bank of feathered sheets is supported upon a feed table 1 in position to be acted upon by combing rolls, one of which is indicated at 2. 15 The bank of sheets is fed to the feed table 1 from a supply table 3, the front end of which is arranged over the rear end of the feed table. The bank of sheets passes from 20 the supply table to the feed table through a curved throat formed between the drum 4 and the curved guides 5. Pressure rolls 6 are located above the drum 4 and act to press the bank of sheets against the drum and thus 25 insure the proper feeding of the bank through the curved throat. The bank upon the supply table rests upon endless bands 7 which extend along the upper face of the table and around the drum 4. The bank 30 upon the feed table 1 rests upon feed tapes 8 which pass over the upper surface of the table and around pulleys 9 and 10. The feed tapes 7 and 8, the drum 4, and pressure rolls 6, are operated in unison to advance or feed 35 forward the bank of feathered sheets at proper intervals through gearing connecting the pulley 10, drum 4, and rolls 6 with a sprocket wheel 11.

The front of the bank of sheets upon the 40 feed table 1 is acted upon by two combing rolls 2, one only of which is shown. These rolls are located on each side of the feed table, and are independently controlled by devices which are fully illustrated in the 45 patent above referred to, so that the combing roll at each side acts until the edge of the sheet at that side has been advanced into proper position to be seized and removed, and is then thrown out of action. The top 50 sheet is advanced by the combing rolls until the front edge of the sheet acts upon the controlling trips 12, when the combing action ceases. The trips 12 are so located that the front edge of the sheet is thus brought between the forwarding or delivery rolls 13 55 and 14. The roll 14 is lowered immediately after the combing rolls are thrown out of action, and the top sheet, which has been separated by the combing rolls, is carried away by the delivery rolls 13 and 14. After 60 the top sheet has been thus removed, and the rear edge of the sheet has passed the rolls 13 and 14, the roll 14 is raised, and the combing rolls are again thrown into action 65 to comb forward the top sheets and bring

the top sheet into position to be acted upon by the delivery rolls.

In order that the sheets may be properly separated by the combing rolls, and individual sheets presented to the delivery rolls, 70 the front edge of the bank of sheets should be such a distance back of the trips 12 that the combing device will effect the proper separation of the sheets in advancing the top sheet into position to be seized by the delivery rolls, since otherwise the second sheet might be advanced sufficiently to be seized by the rolls. At the same time, the distance of the front edge of the bank back of the trips 12 should not be so great that 75 the combing devices will not advance the top sheet sufficiently to bring it into position to be seized by the delivery rolls, since otherwise the sheet will not be taken away by the delivery rolls. The front edge of the bank should therefore be maintained at a substantially fixed distance back of the trips, and this distance will depend upon the separation effected by the combing devices during 80 the time that they are in action.

In order to maintain the front edge of the bank at a substantially fixed point during the separation of the sheets from the front end of the bank, means are provided for controlling the feeding of the bank from 85 its front edge. In the construction shown, the sprocket wheel 11 is actuated to effect the advance or feeding movements of the bank of sheets through a chain 15 passing around the sprocket wheel, around idle wheels 16, and over a sprocket wheel 17 secured to the outer end of a sleeve 18. The sleeve 18 is mounted on a shaft 19 which extends transversely above the front end of the feed table. The ratchet wheel 20 is secured to the sleeve 18, and is arranged to be engaged by a pawl 21 mounted upon a pawl carrying lever 22. The lower end of the pawl carrying lever 22 is provided with a roll arranged to be operated upon by a cam 23 which is secured to 100 the continuously rotating cam shaft 24. The pawl carrying lever is held in engagement with the cam 23 by a spring 24', and when the pawl engages the ratchet wheel 20 the cam 23 acts through the mechanism described to impart a feeding movement to the devices which engage and move forward the bank of sheets. The operation of the bank feeding mechanism is controlled by controlling the engagement of the pawl 21 with the ratchet 20. For this purpose the pawl 21 is connected by means of a link 25 with one arm of a bell crank lever 26, which is pivoted on the pawl carrying lever 22. The other 105 arm of the bell crank lever 26 carries a controlling finger 27 which is arranged to ride over the front of the bank of sheets as the pawl carrying lever 22 is reciprocated by the cam 23. The cam 23 is so shaped that the lower end of the pawl carrying lever 22 is 110 115 120 125 130

advanced to give the pawl 21 its active or feeding movement during the interval after the rear end of the sheet has passed the delivery rolls 13 and 14, and before the combing rolls are again thrown into action. If the front end of the bank is in position to underlie and support the controller finger 27 during the advance movement of the pawl carrying lever, the front end of the bank, 5 acting through the controller finger, holds the pawl 21 out of engagement with the ratchet wheel 20 so that no feeding movement of the bank takes place. If, after the removal of the top sheet, the front edge of the bank of sheets is so far back of the trips 12 that the controlling finger 27 will not ride on the top of the bank, or will ride off of the front edge of the bank during the forward movement of the pawl carrying lever, 10 then the pawl 21 will not be supported, but will drop into engagement with the ratchet teeth on the ratchet wheel 20, and a forward feeding movement will be imparted to the ratchet wheel, and through the connected mechanism to the bank of sheets. The extent of this feeding movement will depend upon the position of the front edge of the bank. If the front edge of the bank is so 15 far forward that the controlling finger 27 rides on the top of the bank during the greater portion of this forward movement, the pawl 21 will not engage the ratchet wheel until it has nearly completed its advance movement, and there will be a comparatively small feeding movement of the bank. If the controlling finger 27 does not ride on the top of the bank during any of its forward movement, then the pawl 21 will act upon the ratchet wheel during its entire 20 feeding movement, and the maximum feeding movement will be imparted to the bank. Feeding movements will continue to be imparted to the bank after the removal of each sheet from the front of the bank, so long as 25 the front edge of the bank after the removal of the top sheet is in position to allow the feeding pawl to operate. The feeding of the bank will cease as soon as the front edge of the bank is brought into position to support the controlling finger 27 during the entire feeding movement of the feeding pawl, and there will be no further feeding of the bank so long as the front edge of the bank 30 continues in such position.

55 The controlling finger 27 is adjustably secured upon the bell crank lever 26 so that its path of travel over the feed board may be varied or adjusted to vary the point where the finger will ride off the front edge of the bank and cause a feeding movement of the bank. This adjustment enables the distance 35 between the front edge of the bank and the trips 12 to be varied in accordance with the character of the sheets to be operated upon, 40 and in accordance with the separation pro-

duced by the combing wheels in a given period.

Having set forth the nature and object of the invention, and specifically described one form of apparatus in which it may be embodied, what I claim is:—

1. A machine for feeding sheets, having, in combination, a sheet separating device arranged to act upon the top of a bank of sheets, mechanism for feeding a feathered bank of sheets to the separating device, and means controlled by the front edge of the bank for throwing the feeding mechanism into action, substantially as described. 75

2. A machine for feeding sheets, having, in combination, a sheet separating device arranged to act upon the top of a feathered bank of sheets, and mechanism acting to feed forward a bank of feathered sheets when the front edge of the bank is back of 85 a predetermined point, substantially as described. 80

3. A machine for feeding sheets, having, in combination, a combing device, means for controlling the combing device by the sheet, 90 mechanism for feeding a bank of feathered sheets to the combing device, and means for controlling the bank feeding mechanism to advance the bank when the front edge of the bank is back of a predetermined point, 95 substantially as described.

4. A machine for feeding sheets, having, in combination, a combing device, means for controlling the combing device by the sheet, mechanism for feeding a bank of 100 feathered sheets to the combing device, means for controlling the bank feeding mechanism to advance the bank when the front edge of the bank is back of a predetermined point, and means for relatively adjusting the controlling means for the combing device and the bank feeding mechanism, 105 substantially as described.

5. A machine for feeding sheets, having, in combination, a combing device, means for 110 controlling the combing device by the sheet, mechanism for feeding a bank of feathered sheets to the combing device, and means for controlling said feeding mechanism from the front edge of the bank adjustable to vary 115 the point at which the front edge of the bank is maintained by the feeding mechanism, substantially as described.

6. A machine for feeding sheets, having, in combination, an intermittently acting 120 sheet combing device, means for presenting a bank of feathered sheets to the combing device, and mechanism controlled by the front edge of the bank for feeding forward the bank between successive operations of 125 the combing device upon the bank, substantially as described.

7. A machine for feeding sheets, having, in combination, mechanism for feeding a bank of feathered sheets, means acting upon 130

- the top of the bank for separating individual sheets therefrom, and means controlled from the front edge of the bank for throwing the feeding mechanism into action, substantially as described.
8. A machine for feeding sheets, having, in combination, a combing roll, mechanism for throwing the roll into action, mechanism controlled by the sheet for throwing the roll out of action, and mechanism controlled by the front edge of the bank after the top sheet advanced by the combing roll has been removed for feeding a bank of sheets to the combing roll, substantially as described.
15. 9. A machine for feeding sheets, having, in combination, a sheet separating device arranged to act upon the top of a bank of sheets, mechanism for feeding a bank of feathered sheets to the separating device, and a device coöperating with the front edge of the bank to control the throwing into action of the bank feeding mechanism, substantially as described.
10. A machine for feeding sheets, having, in combination, a sheet separating device, a device for controlling the operation of the separating device by the sheet, mechanism for feeding a bank of feathered sheets to the separating device, and a controlling device operated when in engagement with the front of the bank to render the bank feeding mechanism inactive, substantially as described.
11. A machine for feeding sheets, having, in combination, a combing roll, mechanism for feeding forward a bank of feathered sheets, and means controlled by the front edge of the bank for maintaining said front edge at a substantially uniform point, substantially as described.
12. A machine for feeding sheets, having, in combination, sheet combing means, mechanism for feeding forward a bank of feathered sheets, means for controlling said mechanism to maintain the front edge of the bank at a substantially uniform point, and means for adjusting said point, substantially as described.
13. A machine for feeding sheets, having, in combination, sheet combing means, mechanism for feeding forward a bank of feathered sheets, means coöperating with the front edge of the bank to render the bank feeding mechanism inactive until the front edge of the bank is back of a predetermined point and to then cause said feeding mechanism to advance the bank, substantially as described.
14. A machine for feeding sheets, having, in combination, a combing roll, mechanism for throwing the roll into action, mechanism controlled by the sheet for throwing the roll out of action, mechanism for feeding a bank of feathered sheets to the roll, a controller arranged to travel over the front of the bank, and connections for causing a feeding of the bank when the controller is unsupported by the bank, substantially as described.
15. A machine for feeding sheets, having, in combination, mechanism for feeding a bank of feathered sheets including a pawl and ratchet, a controller connected with the pawl and arranged to ride over the front of the bank and render the pawl inactive while in engagement with the bank, substantially as described.
16. A machine for feeding sheets, having, in combination, a combing roll, mechanism for throwing the roll into action, mechanism controlled by the sheet for throwing the roll out of action, mechanism for feeding a bank of feathered sheets, and a controller arranged at the front of the bank and connected to prevent the action of the feeding mechanism when engaged by the bank, and to allow the action of the feeding mechanism when free from the front edge of the bank, substantially as described.
17. A machine for feeding sheets, having, in combination, a combing roll, mechanism for throwing the roll into action, mechanism controlled by the sheet for throwing the roll out of action, mechanism for feeding a bank of feathered sheets to the roll including an actuating pawl and ratchet, a controller finger adapted to render the pawl and ratchet inactive while in engagement with the bank, and means acting to move the controller finger along the front of the bank in the direction of feed, substantially as described.
18. A machine for feeding sheets, having, in combination, a combing roll, mechanism for throwing the roll into action, mechanism controlled by the sheet for throwing the roll out of action, mechanism for feeding forward a bank of feathered sheets, means coöperating with the front edge of the bank to render the bank feeding mechanism inactive until the front edge of the bank is back of a predetermined point and to then cause said feeding mechanism to advance the bank, substantially as described.
19. A machine for feeding sheets, having, in combination, a combing roll, mechanism controlled by the sheet for throwing the roll out of action, mechanism for feeding forward a bank of feathered sheets, and means controlled by the front edge of the bank for maintaining said front edge at a substantially uniform point, substantially as described.
20. A machine for feeding sheets, having, in combination, a combing roll, a sheet operated controlling trip for throwing the combing roll out of action, mechanism for feeding a bank of feathered sheets to the combing roll, a device for arresting the feeding action of said mechanism, and a con-

- troller connected to render said arresting device active when engaged by the bank and to render said device inactive when free from the bank, substantially as described.
- 5 21. A machine for feeding sheets, having, in combination, sheet separating means, a controller for controlling the separating means by the sheet, mechanism for feeding a bank of feathered sheets to the separating means, a controller finger arranged to extend 10 across the front edge of the bank, and a stop device operated by said controller finger for preventing the feeding action of the bank by the feeding mechanism when the controller finger is in engagement with the bank, substantially as described.
- In testimony whereof I affix my signature, in presence of two witnesses.
